RETRACTABLE PACK-OFF DEVICE

George Green, Houston, Tex.

Application March 18, 1940, Serial No. 324,481

4 Claims. (Cl. 166—12)

This invention relates to new and useful improvements in retractable pack-off devices.

It is often desirable to cement a well bore below a certain point, or to place a bridge plug of cement within a well bore. It is one object of this invention to provide a pack-off device suitable for use in such instances.

Another object of the invention is to provide an improved pack-off device having means whereby the device may be lowered into a well bore in an inoperative position and adjusted to an operative position after it has been lowered to the point below which it is desired to cement the well bore.

An important object of the invention is to provide an improved pack-off device which may be set whenever desired and may be released and retrieved in its entirety to the ground surface whenever desired; also which is provided with anchoring means which may be set to any desired degree and held at that point, whereby well pressure or other pressure acting upon the packing means does not act to set the anchoring means further, thereby preventing the packing means from setting the anchoring means to such an extent as to deform the casing or prevent the unsetting of the anchoring means.

A further object of the invention is to provide an improved pack-off device which may be positively and easily set, said device having a shear pin disposed therein, whereby, in the event the device becomes stuck or lodged in the well bore, a portion of the device may be retrieved to the top of the well bore by shearing said pin, the remainder of said device being formed of drillable material so that it may be drilled out of the well bore to clear said bore.

Still another object of the invention is to provide an improved pack-off device having an axial support, a packer, pipe engaging elements, and means for displacing said elements upon actuation of said support, whereby the support may be moved longitudinally to displace said pipe engaging elements into gripping engagement with the well casing, and then rotated to disengage the parts so as to leave the gripping elements in a set or anchoring position, and the support free for longitudinal movement to expand the packer.

Another object of the invention is to provide an improved retractable pack-off device so arranged that it may be utilized to retain cement while the latter is setting; also to wash above the cement, and which may be retrieved from the well bore after the cementing operation is completed.

A further object of the invention is to provide

an improved pack-off device in which any pressure existent in the well bore has no effect upon the setting or releasing of said device, and wherein in the unlatching of a J-slot or J-slots is not affected by fluid pressure present in the well bore.

Another object of the invention is to provide an improved pack-off device having means whereby the packer may be lowered into a well bore in an inoperative position and adjusted to an operative position at the desired location, thereby packing off between the lower portion of the well bore and the upper portion, so that said well may be produced through said device.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a longitudinal view, partly in elevation and partly in section, of a pack-off device constructed in accordance with the invention, showing the device in an unset position as it is lowered into the well bore.

Figure 2 is a similar view showing the device in a set position preparatory to the pumping of the cement down the well tubing.

Figure 3 is a longitudinal view, partly in elevation and partly in section, showing the device in a washing position.

Figure 4 is a similar view showing the device in a partially disengaged or loosened position preparatory to the removal of said device from the well bore.

Figure 5 is a horizontal, cross-sectional view taken on the line 5—5 of Figure 1.

Figure 6 is a horizontal, cross-sectional view taken on the line 6—6 of Figure 1.

Figure 7 is a horizontal, cross-sectional view taken on the line 7—7 of Figure 4.

Figure 8 is a horizontal, cross-sectional view taken on the line 8—8 of Figure 4.

Figure 9 is a horizontal, cross-sectional view taken on the line 9—9 of Figure 4.

Figure 10 is a vertical sectional view of the upper portion of the device, showing the J-slots.

Figure 11 is a horizontal, cross-sectional view taken on the line 11—11 of Figure 1.

Figure 12 is a longitudinal view, partly in elevation and partly in section of a slightly modified form of the pack-off device constructed in accordance with the invention, and

Figure 13 is a continuation of Figure 12.

In the drawings, the numeral 10 designates a cylindrical support housing formed of an upper sleeve 11 and a lower sleeve 12. The housing 10 is designed to be connected to a tubing string or other conductor (not shown) and lowered into a well casing A. An elongate tubular mandrel 13 is disposed axially of the housing and has its upper end extending above the housing, and provided with suitable means for connecting the tubing string or other conductor with the device. The upper sleeve 11 of the housing is provided with a plurality of spaced longitudinal grooves 14 formed on its inner wall and extending from the upper end portion of said sleeve downwardly therefrom. An internal collar 15 has a sliding fit within the bore of the sleeve 11 and is formed exteriorly with a plurality of radially-extending, vertical lugs 16, said lugs having a sliding fit in the grooves 14. The engagement of the lugs 16 in the grooves 14 renders the collar 15 incapable of rotative movement with respect to the sleeve 11, but at the same time allows the collar to undergo limited longitudinal movement within said sleeve. A plurality of ordinary friction shoes 17 are provided about the outer wall of the sleeve 11.

Internal screw-threads 18 are formed in the upper end of the sleeve 11, and a bushing 19 has screw-threaded engagement therein with said screw-threads, the bushing 19 being provided with an axial bore 19 through which the mandrel 13 extends. A pair of diametrically-opposed, vertical grooves 20 are provided in the wall of the bore 19, and extend from the upper surface of the bushing 19 downwardly thereinto. A pair of diametrically-opposed, divergent, horizontal slots 21 are formed in the bushing and disposed so as to extend from the bore 19 to the outer wall of the bushing, said slots communicating with the lower extremities of the grooves 20. A pair of diametrically-opposed radial grooves 22 are offset from the bottom of the slots 21 so as to be displaced 90 degrees from the vertical grooves 20. It will be seen (Figures 5, 10, and 11) that the grooves 20, slots 21, and grooves 22 form a pair of diametrically-opposed J-slots 23, the function of which will be disclosed hereinafter. A pair of diametrically-opposed, radially-extending pins 24 are provided on the upper outer surface of the mandrel 13 so as to engage in the J-slots 23.

The lower extremity of the sleeve 11 is recessed and carries internal, left-hand screw-threads 25 which are engaged by external, left-hand screw-threads 26 formed upon the upper reduced end of the sleeve 12. It is pointed out that the reduced end of the lower sleeve telescopes the upper sleeve, whereby said sleeves are flush and present a substantially continuous inner and outer wall. A shear pin 27 passes transversely through the screw-threaded joint between the two sleeves, thus locking them together.

A plurality of rectangular radial openings 28 are provided in the wall of the sleeve 12, said openings being spaced slightly below the screw-threaded joint between the sleeve 12 and the sleeve 11. A plurality of slips 29 are disposed so as to have their gripping faces 30 projecting through the openings 28, while their rearward or inner faces 31 are inclined downwardly and have longitudinal dovetail grooves 32 formed therein. The gripping faces 30 of the slips 29 are made up of teeth so as to prevent upward movement and rotative movement when engaging the inner wall of the casing A.

A slip actuating collar 33, having an axial bore 33', encircles the mandrel 13, and is provided ex-

teriorly with a plurality of upright inclined faces 34 (Figures 1, 2 and 6) for receiving the inclined inner faces 31 of the slips 29. The collar faces 34 have longitudinal dovetails 35 complementary to and engaging the dovetail grooves 32 formed in the slips. The inclined faces of the collar and the dovetails when moved upwardly will cause the slips 29 to be displaced outwardly into gripping engagement with the inner wall of the casing A, and when moved downwardly will cause the slips to be retracted. It is pointed out, that the slips are free to move in these directions only, since they are prevented from longitudinal or lateral movement by the walls of the openings 28.

15 The axial bore 33' has internal left-hand screw-threads 36 at its upper portion, said screw-threads engaging similar external left-hand screw-threads 37 formed upon the mandrel 13, whereby the collar 33 is supported and held in position by the mandrel. The upper collar 15 is provided with internal left-hand screw-threads 38 which substantially match the screw-threads 36 formed in the bore 33'. It will be noted that the lower collar 33 is held against rotative movement by its dovetailed engagement with the slips 29 which are in turn held by the walls of the openings 28. The collar 15, being free to move downwardly, is supported by the engagement of the collar 33 with the screw-threads 37 and the slips 29. The supporting of the collar 15 by the collar 33, and the holding of both collars against rotation, allows the screw-threads 38 to be matched with the screw-threads 36 and form a continuation of the latter. In the position shown in Figure 1, the screw-threads 37, formed upon the mandrel 13, engage the screw-threads 36 formed in the collar 33, and the screw-threads 38 in the collar 15. An inwardly projecting pin 39 is positioned in the wall of the sleeve 12 at a point below the slip actuator or slip-actuating collar 33 so as to limit the downward travel of said collar.

40 An inwardly projecting annular shoulder 40 is formed on the lower extremity of the sleeve 12, and a plurality of radial ports 41 are provided in the wall of said sleeve slightly above said shoulder. A tubular shank or hanger 42, having an outwardly-directed annular flange 43 on its upper end, is positioned so that the under side of the flange 43 engages the upper side of the shoulder

45 40, preventing longitudinal downward motion of the tubular shank or hanger 42. The shank 42 is provided with a plurality of radial ports 44 spaced slightly below the flange 43, and is of such diameter that its outer surface has a sliding fit in the shoulder 40, thereby closing the ports 44; while the outer periphery of the flange 43 has a similar engagement with the inner wall of the sleeve 12 and thereby closes the ports 41 (Figure 1). It will be readily seen by an examination of the drawings, that upward movement of the shank 42 with respect to the sleeve 12 will cause both the ports 41 and the ports 44 to be uncovered, whereby communication is set up between the bore of the shank 42 and the annular space 50 outside the sleeve 12.

Internal left-hand screw-threads 45 are formed in the lower end of the shank 42. An internal annular flange 46 is spaced upwardly from the screw-threads 45 within the shank, and has a sliding fit on the mandrel 13. A tubular head or plug 47 has an upstanding reduced pin 48 formed on its upper end, and provided with external left-hand screw-threads 48' and internal left-hand screw-threads 49. The pin telescopes the lower 55 end of the shank and the threads 45 engage the

threads 48'. External left-hand screw-threads 50 are provided upon the lower end of the mandrel 13 and engage the screw-threads 48. A plurality of radial ports 51 are formed in the wall of the mandrel 13 and spaced slightly above the screw-threads 50 and below the flange 46, when the device is lowered into the well. A resilient packing ring 52 encircles the mandrel 13 and is positioned immediately below the flange 46, thereby closing or shutting off communication through the ports 51.

The lower end of the head is enlarged and formed with an outwardly-directed, annular shoulder 53. A plurality of suitable elastic packing rings 54 rest upon the shoulder surrounding the head and the shank. It will be noted, that the packing rings 54 are separated by suitable flat spacer rings 55. The packing rings engage the lower extremity of the sleeve 12 when the device is set and the rings are in a packed-off position.

The head 47 is formed with an axial bore 56 which has a suitable poppet valve assembly 57 mounted in its lower end. The valve assembly 57 includes a valve 58 having an elongate valve stem 59 extending upwardly through a spider 60 which is screwed into the bore 56. The upper end of the valve stem 59 has a nut 61 screwed thereon, and a suitable coil spring 62 is confined between said nut and the spider 60. The spring will constantly urge the valve upwardly into a seated position against a seat 63 on the bottom of the head. Pressure acting downwardly through the bore 56 will act upon the upper surface of the valve 58 to force the same downwardly against the compression of the spring 62, and open the valve.

In the operation of the device, the assembly is lowered into the well bore in the position shown in Figure 1. In this position, the pins 24 are engaged in the grooves 22, and the slips 29 are in a retracted position. When a suitable or desirable point is reached in the well bore, the mandrel 13 is rotated by means of the tubing (not shown) from which the device is suspended. The sleeve 11 of the housing 10 will be held against rotation by the friction shoes 11', while the mandrel is rotated anti-clockwise through 90 degrees. This rotation will unlock the J-slot mechanism and allow the pins 24 on the mandrel 13 to be moved upwardly in the grooves 20. Emphasis is laid upon the fact that any fluid pressure present in the well bore will have no effect upon the unlatching of the J-slots. The upward movement of the mandrel 13 will force the collar 33 to move upwardly within the inclined faces of the slips 29, thus displacing the slips outwardly into engagement with the inner wall of the well casing A (Figure 2). Subsequent upward movement of the mandrel 13 will cause the collar 33 to move upwardly and press the slips into snug engagement with the inside wall of the well casing. The slips may be set as tightly as desired without affecting the movement of the mandrel through the bore 33' of the collar 33. It should be noted that the collar 33 is an annular member which will be wedged in between the slips and the friction of such wedging tends to retain the collar in position to retain the slips against the casing. The slips are set to the desired point at this step of the operation. Any pressure acting upon the packing rings will tend to engage them more snugly with the wall of the casing A, but will not tend to set the slips any tighter.

When the slips have been set sufficiently tight, the mandrel is rotated clockwise. The lower portion of the device, including the packing rings and the shank 42 are free to rotate with the mandrel. However, the upper portion including the housing is held against clockwise rotation by the action of the gripping faces 30 of the slips. Therefore, the screw-threads 37 on the mandrel will unscrew from the screw-threads 36 in the collar 33, and will screw into the screw-threads 38 in the collar 15. This is possible, because, as pointed out hereinbefore, the screw-threads 36 and 37 are held in a matched position due to the incapability of the collar 33 and the sleeve 15 to undergo rotative movement with respect to each other.

The rotation of the mandrel 13 is continued until the screw-threads 37 are entirely free of the screw-threads 36. This point may be ascertained beforehand by determining the number of revolutions necessary, or by a slight upward movement of the tubing at the well head during the operation. The mandrel is now moved upwardly to move the packing rings 54 upwardly into engagement with the lower extremity of the sleeve 12. Additional upward movement will expand the packing rings and distort them into a packed-off position. Any desirable and suitable amount of tension may be placed on the tubing and mandrel to expand the packing rings into a packed-off position. In this manner a very efficient and complete packing off is had. As may be seen in Figure 2 of the drawings, the packing means, when in a packed-off position, are in such a position as to be expanded by any fluid pressure present within the well bore. Also, the slip setting collar 33 is disengaged from the threads 37 on the mandrel 13. The disengaging of the collar prevents any force or element present in or about the device from setting the slips too tightly, and thereby rendering their disengagement difficult or deforming the casing.

It will be noted, that the ports 41 and 44 have been uncovered by the hereinbefore described operations, but that the ports 51 remain closed so that fluid may not pass from the bore of the mandrel 13 through the ports 41 and 44. While the device is in the position shown in Figure 2, cement is introduced into the bore of the mandrel by any suitable means, and allowed to flow through the bore 56 of the head 47 and open the poppet valve 57, from where the cement flows into the well bore and the surrounding formation.

The next operation is the further clockwise rotation of the mandrel. Since the head 47 and shank 42 are held against rotation by the engagement of the packing rings, the aforesaid rotation of the mandrel 13 will break the joint between the screw-threads 50 and the screw-threads 49. Thus the mandrel 13 will move upwardly with respect to the shank 42, and the ports 51 will be exposed above the packing ring 52 and the flange 46 with the threads 49 and 50 still in engagement. Water, or any other suitable wash-down liquid, may now be pumped down the bore of the mandrel to pass outwardly through the ports 51, and upwardly and outwardly through the ports 44 and 41 to the annular space between the housing 10 and the inside wall of the casing A. The washing operation is continued until all of the cement has been washed out of the bore of the tubing and the mandrel and upwardly out the top of the well casing, or this operation may be reversed and the fluid pumped down through the casing and up through the mandrel 13 and tubing. This posi-

tion of the device is shown in the drawings in Figure 3.

Further clockwise rotation of the mandrel will cause the screw-threads 50 to become completely disengaged from the screw-threads 49. Of course, the screw-threads 37 will continue to screw upwardly into the screw-threads 38. Downward movement of the mandrel will carry the collar 15 downwardly within the housing 10, causing the lower surface of the collar to strike the upper side of the slip actuating collar 33 and thereby drive the collar 33 downwardly, thus releasing the slips 29. Subsequent upward movement of the tubing and mandrel within the well bore will raise the collar 15 within the housing 10, causing the collar to strike or engage the lower side of the bushing 18 and raise the housing, thereby releasing the packing rings from their packed-off position and allowing the entire device to be removed from the well bore. Thus, as may be seen, the pack-off device may readily be unset and removed from the well bore in its entirety.

It is pointed out, that if, for any reason, the device becomes stuck in the well bore, the mandrel 13 may be rotated clockwise until the screw-threads 37 reach the uppermost position of the screw-threads 38. At this point, further rotation of the mandrel will cause the collar 15 and the sleeve 11 to rotate, thereby shearing the pin 27 and allowing the sleeve 11 to be unscrewed from the sleeve 12. The mandrel 13, along with the sleeve 11 and the collar 15, may now be removed from the well bore. Thus a pack-off device is provided which is quickly and easily set and unset in a well bore regardless of any fluid pressure that may be present, and which may be removed from the well bore in its entirety so as to leave the well bore clean of obstructions; also a portion of said device may be removed from the well bore in the event the device becomes stuck.

In Figures 12 and 13 there has been shown how this structure may be used in what is commonly called a production packer. In many wells it is desirable to insert a packing on the tubing through which the well is produced. This is for the purpose of sealing above the producing sands so that the fluid will be forced to flow through the tubing and not around it. It is especially adaptable where the casing above the producing sands has begun to leak, thereby allowing a fluid such as salt water to enter the producing sands; however, by using this packer, this flow of fluid may be sealed off from the producing sands.

The structure shown in Figures 12 and 13 is identical to that shown in the rest of the drawings, except that the poppet valve 57 is left off, and a perforated bull-nose screen 65 is screw-threadedly attached to the lower end of the head 47. The packer is run into the well bore, as is the pack-off device, to a point above the producing sands; said packer is set in the same manner as the device hereinbefore described. The mandrel may be rotated to open the port 51 so that the mud may be washed out of said suspending

tube and device, so as to allow the well to produce and flow into the screen 65 and up through the mandrel and tubing, thus providing a producing packer. It is pointed out that when the well begins to flow, the mandrel is rotated in a counterclockwise direction so as to move the port 51 downwardly, thereby closing the same, and allowing said fluid to flow up the tubing. In the event high pressures are encountered, they will 10 act upon the bottom of the packing and will act to seal the packing tighter; said tool may be released and taken out of the well in the same manner as the pack-off device.

Various changes, alterations and modifications 15 may be made in the size, shape and arrangement of the herein described elements, within the scope of the appended claims.

What I claim and desire to secure by Letters Patent is:

20 1. A well pack-off device including, a tubular mandrel, a support housing carried by said mandrel, slips carried by said support, a slip actuator collar connected with said mandrel for longitudinal movement thereon, and to be set in said slips by upward movement thereof, and a slip actuator collar releasing member connected with said mandrel above the slip actuator collar relative to the slips to release them from engagement.

25 2. A well pack-off device including, a tubular mandrel, a support housing on said mandrel, a slot in said support, a pin on said mandrel received in said slot, slips carried by said support, a slip actuator screw threaded on said mandrel for longitudinal movement thereon, and a slip 30 releasing member screw threaded on said mandrel for longitudinal movement thereon and for engaging said slip actuator to move it relative to the slips to release the same.

35 3. A well pack-off device including, a longitudinal mandrel, means operable by the mandrel for anchoring the device in a well casing, means operable by the mandrel for packing off the device in a well casing, a valve for shutting off upward flow through the mandrel, fluid admitting 40 means in said mandrel for admitting washing fluid to the interior of the mandrel above the valve and which means is normally closed, and means for moving the mandrel to open the fluid admitting means while the device is anchored and packed off.

45 4. A well pack-off device including, a housing, a mandrel, a slip actuating collar connected to the mandrel, an upwardly tapering face on said collar, slips slidably carried in said housing, said 50 mandrel being moveable upwardly of said housing for setting said collar within said slips to anchor the housing, a rotatable connection to release said mandrel from said actuating collar, a packer carried by the mandrel, said slip actuating collar being held against upward movement by the slips so that longitudinal movement of the mandrel effects the setting of the packer thereagainst.

GEORGE GREEN.
